UNITED STATES PATENT OFFICE

EMIL FAHR, OF DETROIT, MICHIGAN

ARTIST'S KIT

Application filed February 2, 1929. Serial No. 337,118.

My invention relates to a new and useful improvement in an artist's kit and has for its object the provision of a kit adapted for use for artists, so arranged and constructed 5 as to afford a maximum convenience and at the same time be durable and inexpensive to manufacture.

Another object of the invention is the provision of a kit which will serve to support 10 in spaced relation various pieces of canvas, a palette and a paint pot container.

Other objects will appear hereinafter.

The invention consists in the combination and arrangement of parts hereinafter described and claimed.

The invention will be best understood from a reference to the accompanying drawings which form a part of this specification, and in which,

20 Fig. 1 is a perspective view of the invention.

Fig. 2 is a central sectional view of the invention showing it closed.

Fig. 3 is a sectional view taken on line 3—3 25 of Fig. 2.

The invention comprises a box-like structure 7 having a cover 8 hingedly mounted thereon. The side walls 9 and 10 of the box-like structure are provided with a plurality 30 of grooves 11 in which may engage strips of canvas 12 held in spaced relation. A wider groove 13 is formed in the side walls 9 and 10 to accommodate the palette 14. The box-like structure is made of sufficient size that these strips 12 and the palette 14 will terminate with their upper edges well inwardly 35 of the upper edge of the box so that a separate box-like structure 15 may be positioned interiorly of the box and rest upon the edges of the members 12 and 14, the cover 8 being formed so as to receive the upper edge of the box-like structure 15. This box-like structure 15 will serve as a container or receptacle 40 for paint pots 16. Spring clips 17 are mounted on the inner surface of the cover to retain in position the brushes 18.

With a kit constructed in this manner, an artist may transport conveniently from place 45 to place all of the articles needed in paint-

ing, these articles being retained in compact relation.

While I have illustrated and described the preferred form of my invention, I do not wish to limit myself to the precise detail of 55 structure shown but desire to avail myself of such variations and modifications as come within the scope of the appended claims.

Having thus described my invention, what I claim as new and desire to secure by Letters Patent is:

1. An artist's kit of the class described comprising: a box-like structure having oppositely positioned side walls, each of said side walls having formed on its inner face, a plurality of vertically extending grooves, the grooves in one of said side walls each being in alignment with one of the grooves in the opposite side wall; a paint pot container positioned in said box-like structure and adapted 65 to project outwardly thereof; and a cover swingably mounted on said box-like structure for engaging said paint pot container.

2. An artist's kit of the class described having opposite side walls, each provided with a plurality of grooves, each of the grooves in one of said side walls being in alignment with one of the grooves in the other side wall, one of said grooves in each of said side walls being larger than the remainder for the reception of a palette, the remainder of said grooves being adapted for the reception of edges of canvas strips; a cover swingably mounted on said box-like structure; and spring clips mounted on the under surface 80 of said cover for engaging and retaining in position paint brushes.

In testimony whereof I have signed the foregoing specification.

EMIL FAHR. 90
